UNITED STATES PATENT OFFICE.

SIMON GORDON, OF WASHINGTON, DISTRICT OF COLUMBIA.

HORSESHOE.

No. 893,481.

Specification of Letters Patent.

Patented July 14, 1908.

Application filed March 18, 1908. Serial No. 421,830.

To all whom it may concern:

Be it known that I, SIMON GORDON, a citizen of the United States, residing at Washington city, in the District of Columbia, have 5 invented a new and useful Improvement in Horseshoes, of which the following is a specification.

The object of my invention is to provide a horse shoe which shall cost but little and 10 may be made in varying sizes and so constructed as to prevent slipping on icy or slippery pavements, and it consists in the special construction of horse shoe hereinafter described which is formed in one piece of malleable iron or steel and which is provided 15 with three sets of calks of different elevations for the purposes hereinafter more fully described with reference to the drawing, in which

20 Figure 1 is a bottom face view of the shoe. Fig. 2 is a perspective view of the bottom of the same, and Fig. 3 is a cross section on line 3—3.

25 In the drawing, A represents the body of the shoe, the outer portion *a* of which is made relatively thin and is provided with nail holes by which it is fastened on to the horse's hoof.

30 The inner portion of the shoe is made much thicker as seen at *c* and is provided with integral teeth or permanent calks *d* *d'*. These permanent calks are made with blunt 35 face calks *d* and with the alternate calks *d'*, much lower than the adjacent ones and terminating in sharp chisel faces with inclined sides, so that when the higher calks *d* wear away, the sharp edges of the intermediate calks *d'* will come into bearing contact and will thus prevent the shoe from slipping after 40 the shoe is partly worn out. It will be seen that the permanent calks *d* and *d'* extend outwardly from the thicker inner portion *c* of the shoe so that both the bases and tops of these permanent calks are beyond the flat 45 outer portion of the shoe. This gives greater prominence to the calks and prevents the accumulation of ice and snow between them, for the spaces between calks *d* and *d'* are not only of tapering form, but are also entirely 50 open both on the inner and outer sides of the shoe.

55 At the toe of the shoe there is an enlargement *B* of the same elevation as the permanent calks *d* but extending entirely across the width of the shoe, and at the heels there

are corresponding enlargements *B'* *B'* of equal elevation with the toe enlargement *B* and extending entirely across the shoe. All of these enlargements *B*, *B'*, *B'* are formed with undercut dovetail grooves into which 60 are driven detachable wedge shaped calks *e* *e'* whose bearing edges extend beyond the plane of calks *d* and are provided for very sleety conditions, as an especial safeguard.

At the heels of the shoe a connecting 65 bridge piece *E* extends across the frog and serves to protect the same. This bridge piece is formed in one piece with the rest of the shoe, the entire shoe, with the exception of the detachable calks *e* *e'*, being all made in 70 one piece preferably of malleable iron or steel and is very cheaply made. The shoes are to be formed in a large number of different sizes, varying from each other in shape, weight and size, so as to permit one to be 75 easily selected to suit the particular hoof of the horse without any bending, heating or fitting, thus greatly reducing the labor of shoeing as well as the cost of the shoes.

I am aware that horse shoes have been 80 heretofore made showing the separate elements of my shoe, but I do not know that the specific features of construction shown and described have ever been heretofore combined in a single shoe.

85 In connection with my shoe I may, if desired, use any form of pad.

I claim—

1. A horse shoe, consisting of a body portion having on each side two levels, the inner 90 level being of greater thickness than the outer level and having on the inner level two series of permanent calks, extending from the thicker inner portion, one series having flat bearing faces and the alternating series being 95 shorter and formed with chisel-shaped edges and said shoe having toe and heel enlargements extending across the full width of the shoe and having outer bearing faces lying in the same plane as the flat bearing faces of the 100 permanent calks of the sides of the shoe.

2. A horse shoe, consisting of a body portion having on each side two levels, the inner level being of greater thickness than the outer level and having on the inner level two 105 series of permanent calks, extending from the thicker inner portion, one series having flat outer bearing faces and the alternating series being shorter and formed with chisel-shaped edges and said shoe having toe and heel en- 110

largements extending across the full width of the shoe and having outer faces lying in the same plane as the flat bearing faces of the permanent calks at the sides of the shoe, and 5 having dovetail grooves formed across the said toe and heel enlargements, and provided with detachable calks with bearing

edges having a greater projection than the flat bearing faces of the permanent calks along the sides of the shoe.

SIMON GORDON.
